DESCRIPTION

FIG. 1 is a front perspective view of a hand bag;
FIG. 2 is a front view of the hand bag;
FIG. 3 is a rear view of the hand bag;
[FIG. 4 is a left side view of the hand bag;
FIG. 4 is an elevation view of the hand bag's right side;
[FIG. 5 is a right side view of the hand bag;
FIG. 5 is an elevation view of the hand bag's left side;
FIG. 6 is a top view of the hand bag; and,
FIG. 7 is a bottom view of the hand bag.

The broken lines depict portions of the hand bag in which the design is embodied that are not considered part of the claimed design.
